UNITED STATES PATENT OFFICE

1,971,907

GASEOUS DISCHARGE DEVICE

Clifton G. Found, Schenectady, N. Y., assignor
to General Electric Company, a corporation of
New York

Application July 2, 1928, Serial No. 289,696
Renewed October 26, 1933

5 Claims. (Cl. 176—122)

The present invention relates to electrical discharges in gases, and in particular comprises new gaseous glow devices adapted for operation with alternating current.

5 It is the object of my invention to provide a convenient form of thermionic arc device for illumination or other purpose, which will be operable with alternating current at ordinary distribution potentials.

10 Prior to my invention electric discharge devices having a positive column of high luminosity have been constructed for operation with alternating current by providing two anodes together with a single cooperating cathode. Such devices required a three wire supply circuit, and in some cases are subject to arcing between the anodes.

In accordance with my invention I have provided gaseous discharge devices, which operate with a long positive column discharge, and having electrodes at opposite ends which function reversibly as cathode and anode will respect to one another.

25 In thermionic gaseous devices having an elongated envelope in which the distance between the electrode is long relative to the distance of the electrodes from the walls, the walls of the envelope appear to have a grid-like effect in resisting the starting of a discharge. Apparently the walls become negatively charged and a discharge 30 will not start through the gas between the electrodes until enough positive ions have been formed by a high voltage impulse to discharge the negative charge on the walls. I have discovered that in such an elongated envelope under suitable conditions successive electric discharges can be operated in opposite directions without requiring the continuous operation of a high voltage ionizing means or an operating voltage which is appreciably higher than a continuous or direct current discharge would require in an envelope of the same size and shape.

40 Apparently under suitable conditions of gas pressure and the geometrical relation of the electrodes to one another and to the envelope, the time required for a complete diffusion and discharge of the positive ions is greater than the time during which, in an alternating current cycle, the impressed voltage is too low to support a discharge.

45 My invention will be pointed out with greater particularity in the appended claims and will be more fully understood by reference to the accompanying drawing as explained by the following description.

55 In the drawing Fig. 1 is a perspective view of a

gaseous glow lamp embodying my invention, part of the envelope being removed; Fig. 2 is a longitudinal section of an electrode and adjacent parts; and Fig. 3 is a diagram of an electrical circuit suitable for operating my improved lamp.

60 Referring to Fig. 1, the lamp illustrated comprises an elongated tubular envelope 1, constituted of glass, quartz, or other suitable transparent material, and having at opposite ends re-entrant stems 2, 3, through which pass respectively 65 current conductors 4, 5 and 6, 7.

Upon these respective pairs of conductors are mounted the electrodes 8, 9 each of which function alternately as cathode and anode. The structure of these electrodes is shown in detail in 70 Fig. 2. As these electrodes operate each alternately as anode and cathode they may be similar or identical in structure. The electrodes illustrated comprise a hollow body or cylinder 10, which is heated by radiation or conduction 75 or both from a heater 11 which is located within the cylinder 10, the electric circuit being constituted by the conductor 5 connected to one of the terminals of the heater 11, the cylinder 10, which is welded or otherwise joined to the opposite terminal of the heater, and the conductor 5, to which the cylinder 10 is in turn joined. The cylinder 10 which may consist of a foundation metal such as nickel, iron or platinum, is 80 coated with thermionically active material, such as an alkaline earth oxide. For example, it may be coated with a layer of barium carbonate preferably admixed with a cellulose compound binder, the carbonate later being decomposed by heating the foundation metal to a temperature of 85 about 1300° C. in a maintained vacuum. The heater 11 consists of a suitable refractory metal such as tungsten or molybdenum. Surrounding the cylinder 10 is a shield 12, which preferably 90 is connected to the conductor 5, and serves both to conserve the heat required for maintaining the cathode at an operating temperature and to 95 reduce deposition of evaporated cathode material on the wall of the envelope.

100 Thermionic electrodes, such as herein described, having a broad emitting surface are superior to ordinary filamentary cathodes for gaseous glow devices and will be briefly referred to as broad cathodes. The surface area and electron emissivity of such a broad thermionic cathode should be chosen to give a total electron emission which is capable of supporting the luminous discharge without causing the fall of potential at the cathode to rise above the value at which the electric disintegration becomes ap- 110

preciable. If the electron emission is sufficiently high then the effect of positive ion bombardment on the cathode is negligible and the lamps have a long life.

5 After the electrodes have been formed and degassed and the vitreous envelope has been baked and evacuated of gas, a luminosity-producing gas or vapor, such as neon, helium or mercury vapor is admitted. For example, neon 10 at a pressure of about 1.5 to 3 millimeters of mercury may be employed.

As shown in Fig. 3, the terminals of the electrodes 8, 9 may be connected to an auto-transformer 14 which is connected to a supply circuit 15. The wires 4, 5 and 6, 7 are connected respectively by the conductors 16, 17 and 18, 19 to the sections 20 and 21 of the transformer secondary for the supply of electrode heating current. In 20 order to start the lamp into operation a high potential impulse is impressed upon it by any suitable means examples of which are well known. For illustrative purposes, a starting device has been shown comprising a mercury switch 22 which is connected to an intermediate point of the transformer 14 through a resistance 23 and an end terminal by the conductor 24 in circuit with a magnet 25. When the supply circuit 15 is energized the magnet 25 lifts its armature 26, thereby interrupting the flow of current in the 25 switch circuit and impressing the resulting high voltage impulse on the lamp terminals. These terminals when up to temperature are emitting electrons and ready to start into operation a thermionic discharge when the high voltage discharge 30 is impressed upon them.

A discharge, when once started, will continue to operate at ordinary lighting circuit voltage, that is, the voltage of 110 to 220 volts. As an illustrative example, a lamp having a tubular 40 envelope about 40 inches long (about one meter) and 1½ inches (about 4 c. m.) in diameter provided with broad thermionic electrodes at opposite ends, and containing neon gas at a pressure of two millimeters of mercury may be operated 45 steadily to produce a luminous discharge with alternating, sixty cycle current of about one ampere and an impressed voltage of about 220 volts. A shorter lamp can be operated with a lower voltage. Such a discharge will have an 50 over-all luminous efficiency of about 10 lumens per watt. A preponderate proportion of the voltage consumed in such a lamp is consumed in the gaseous discharge and only a small proportion at the electrodes.

What I claim as new and desire to secure by Letters Patent of the United States is:

1. An alternating current arc lamp comprising a sealed envelope, a luminosity-producing gas therein, and cooperating electrodes spaced apart 80 a distance which is long relative to their size and comprising hollow metal bodies, electric resistance heaters within said hollow bodies, leading-in conductors therefor sealed into said envelope, and a material coating said hollow bodies having a higher electron emissivity than said bodies, each of said hollow metal bodies having a surface area such that the anode drop in said lamp is substantially zero.

2. An alternating current positive column arc lamp comprising an elongated tubular sealed envelope, a luminosity producing gas therein, and cooperating electrodes located at opposite ends of said envelope and serving alternately as anode and cathode, a coating of material of high electron emissivity on each of said electrodes, each of said electrodes having a surface area such that the anode drop in said lamp is substantially zero.

3. An alternating current positive column arc lamp comprising an elongated tubular sealed envelope, a luminosity producing gas therein, and cooperating electrodes, each comprising a metallic body, a coating of high electron emissivity on said body and a tubular metallic shield extending about said body and connected thereto, located at 100 opposite ends of said envelope and serving alternately as anode and cathode, each of said electrodes having a surface of such area that the anode drop in said lamp is substantially zero.

4. An alternating current lamp comprising a sealed envelope containing a luminosity-producing gas, cooperating electrodes therein which serve alternately as anode and cathode, each of said electrodes having a surface of high electron emissivity, and means to heat each of said electrodes, the surface area of each of said electrodes being such that the anode drop in said lamp is substantially zero.

5. An alternating current lamp comprising a sealed envelope containing a luminosity-producing gas and cooperating thermionic electron-emitting electrodes which serve alternately as anode and cathode, the surface area of each of said electrodes being such that the anode drop in said lamp is substantially zero.
